CLAIM

The ornamental design for an anti-gnawing squirrel baffle, as shown and described.

DESCRIPTION

FIG. 1 is a top, front, right side perspective view of an anti-gnawing squirrel baffle showing my new design; FIG. 2 is a bottom, rear, right side perspective view thereof; FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof; and,

FIG. 9 is a perspective view of one component piece of the anti-gnawing squirrel baffle, shown separately for clarity.

1 Claim, 9 Drawing Sheets
